(57) **ABSTRACT**

The invention relates to a sole (1) of a shoe, particularly of an athletic shoe, wherein the sole (1) has an extension in a longitudinal direction (L) and an extension in a vertical direction (V) perpendicular thereto, wherein a number of recesses (2) is introduced into the sole (1), wherein the recesses (2) extend in a transverse direction (Q) perpendicular to the longitudinal direction (L) and perpendicular to the vertical direction (V) and permeate the sole (1) at least in part. In order to influence the spring behaviour of the sole in a desired, specified manner, according to the invention, there is a first group of recesses (2') which, without external forces on the sole (1), are larger in the vertical direction (V) than

(Continued)

in the longitudinal direction (L), and that there is a second group of recesses (2'') which, without external forces on the sole (1), are smaller in the vertical direction (V) than in the longitudinal direction (L), wherein at least in sections, at least one row (3, 4) of recesses (2', 2'') is arranged adjacent to each other in the longitudinal direction (L), wherein a recess (2'') of the second group is arranged between two recesses (2') of the first group.

FIG. 2

1

SOLE OF A SHOE, PARTICULARLY AN
ATHLETIC SHOE

This application is a U.S. National Stage application, filed pursuant to 35 U.S.C. § 371, of international application no. PCT/EP2018/061934, filed on May 8, 2018, the contents of which is incorporated herein by reference in its entirety.

The invention relates to a sole of a shoe, particularly of an athletic shoe, wherein the sole has an extension in a longitudinal direction and an extension in a vertical direction perpendicular thereto, wherein a number of recesses is introduced into the sole, wherein the recesses extend in a transverse direction perpendicular to the longitudinal direction and perpendicular to the vertical direction and permeate the sole at least in part.

In the case of sports shoes, an attempt is made to give the sole a certain and desired spring behaviour by means of the geometric design of the sole. This means that the sole exhibits a desired deformation behaviour in the vertical direction when subjected to the weight of the wearer of the shoe, in particular a certain characteristic curve between the force applied and the strain in the vertical direction.

A sole of the type mentioned above is known from U.S. Pat. No. 2,983,056 A. The body of the sole is provided here in transverse direction with a plurality of recesses, which are formed circularly, laterally on the sole, thus seen in transverse direction. The recesses have different diameters, whereby one with a smaller diameter is located between two recesses with a larger diameter. Such recesses can be used to influence the spring or damping behaviour of the sole.

The invention is based on the object to further develop a shoe sole of the type mentioned above in such a way that it becomes possible to influence the spring and damping behaviour of the sole in a desired, predetermined improved manner.

The solution of this object by the invention is characterized in that there is a first group of recesses which (without external forces on the sole) are larger in the vertical direction than in the longitudinal direction, and that there is a second group of recesses which (without external forces on the sole) are smaller in the vertical direction than in the longitudinal direction, wherein at least in sections, at least one row of recesses is arranged adjacent to each other in the longitudinal direction, wherein a recess of the second group is arranged between two recesses of the first group.

At least in sections an upper row of recesses and a lower row of recesses can thereby be arranged above one another in the vertical direction. The two rows are in this case preferably arranged relative to each other in such a way that a recess of the first group lies vertically above a recess of the second group.

The recesses penetrate preferably at least partially the sole completely in the transverse direction.

The recesses extend thereby preferably along a straight line, they are thus designed straight and linear respectively.

Without external forces on the sole, preferably the largest dimension of a recess in a first direction is thereby at least 150%, preferably at least 180%, of the largest dimension of the recess in a second direction perpendicular to the first direction. Thereby, it is specifically preferred that the recesses, seen in the transverse direction, have a peripheral contour which has the shape of an eight. The recess has in this case in a central region preferably a restriction with a minimum extension which is at most 90%, preferably at most 80%, of the largest dimension in the second direction.

2

The largest dimension is thereby preferably between 8 mm and 18 mm, specifically preferred between 10 mm and 15 mm.

The wall thickness of the material of the sole remaining between the recesses is preferably substantially constant at least in sections. Insofar, it is preferred that the wall thickness at least in sections is in a range between 80% and 120% of an average value of the wall thickness (the average value of the wall thickness is the arithmetic mean, which is determined for the respective wall thicknesses between adjacent recesses over a given defined area of the lateral surface of the sole).

The sole consists preferably of polyurethane material, thermoplastic polyurethane (TPU) or thermoplastic elastomer (TPE) or comprises at least this material. The material of the sole is thereby preferably foamed.

The material of the sole has preferably a density between 0.20 and 0.50 g/cm³. It has preferably a hardness between 30 and 50 Asker C.

20 The sole can be designed as a midsole. Thereby, it is possible that an outer sole is placed below the midsole.

The recesses are preferably arranged in the longitudinal direction over at least 33% of the total longitudinal extension of the sole. They are preferably arranged at least in a midfoot region and a rearfoot region of the sole.

25 The proposed design of the sole makes it possible to influence the control of the spring and cushioning properties or the hardness of the sole in a simple way. By the design of the recesses it is possible to realize a desired spring deflection when the sole is loaded with the weight of the wearer of the shoe equipped with the sole.

30 The present invention is based on the use of so-called "Mechanical Meta Material", in which it is intended that various rows of openings (known are mainly round or oval recesses in cross-section) of different sizes are or are to be introduced into the sole in order to achieve a certain spring or cushioning behaviour of the sole. This enables "Engineered Damping", in which the spring or damping properties obey a desired characteristic curve.

35 40 When a deformation force—caused by the weight of the wearer of the shoe—is applied, the resulting cells collapse in a special way so that special spring or damping characteristics can be realized.

45 In this respect, a "programmable folding or collapsing" of the sole structure is achieved, so to speak, since the structure itself forms a coherent system and the individual material sections are interdependent.

50 55 The advantages of the proposed structure can lead to a "negative stiffness", i.e. if the sole is slightly compressed in a vertical direction, the sole collapses in a defined way. It is also possible to structure the sole in the way described above in such a way that it has a sufficient degree of elasticity on the one hand and absorbs deformation energy as a result of a deformation force on the other.

55 60 In the drawings an embodiment of the invention is shown. FIG. 1 shows a sole of a sports shoe, wherein said sole comprises a midsole and an outsole,

65 FIG. 2 shows the section "X" according to FIG. 1 in more detail, seen in a transverse direction perpendicular to the longitudinal direction of the sole and perpendicular to the vertical direction, and

60 65 FIG. 3 shows a recess in the sole with details of its geometry.

FIG. 1 shows a sole 1, which extends in a longitudinal direction L (corresponding to the longitudinal axis of the shoe with the sole) and in a vertical direction V (the vertical direction V indicates the direction when the shoe or the sole

is standing on the ground when used as intended). Furthermore, sole 1 extends in a transverse direction Q, which is perpendicular to both the longitudinal direction L and the vertical direction V.

Sole 1 is here designed as a midsole, to the upper side of which the (not shown) shoe upper is attached in the known manner. An outer sole 6 is attached to the bottom of the sole.

Recesses 2 are incorporated into the sole 1. Preferably, these recesses extend in transverse direction Q over the entire width of the sole 1. Details on the design and arrangement of recesses 2 are shown in FIGS. 2 and 3. For this purpose, FIG. 2 shows the detail "X" according to FIG. 1 and FIG. 3 shows the geometrical design of a preferred design of a single recess 2.

As can be seen in FIG. 2 in combination with FIG. 1, two rows 3 and 4 of recesses 2 are incorporated into the sole 1. Thereby, two groups of recesses 2 are employed:

A first group of recesses 2' is designed in such a way that—without external forces on the sole 1—the recesses 2' are larger in vertical direction V than in longitudinal direction L. Then there is a second group of recesses 2'', which—again without external forces on the sole 1—are smaller in vertical direction V than in longitudinal direction L. As can be seen in FIG. 2, in each row 3, 4 in longitudinal direction L the recesses 2', 2'' are arranged next to each other in such a way that between two recesses 2' of the first group a recess 2'' of the second group is arranged.

The individual recesses 2', 2'' are each designed in such a way that they have the shape of an "eighth" when viewed in transverse direction Q. Reference is made in particular to FIG. 3.

Accordingly, each recess 2', 2'' has in a first direction R1 a largest dimension G (which is preferably between 10 mm and 15 mm); in a second direction R2, which is perpendicular to the first direction R1, the largest dimension of recess 2', 2'' is denoted with K. The dimension G is preferably at least 150% (particularly preferably even at least 180%) of the dimension K.

In the central area along the extension in the first direction R1, the recess 2', 2'' has a restriction 5 (which results in the shape of an "eighth"), so that the recess 2', 2'' has a minimal extension k here. This minimum extension k is preferably at most 90%, especially preferably at most 80%, of the dimension K.

The remaining wall thickness t, which results between adjacent recesses 2', 2'', must also be mentioned. This is denoted in FIG. 2 at various points. If one determines an (arithmetic) mean value between the respective wall thicknesses t over a selected area (such as the area shown in FIG. 2), it is preferably intended that the wall thickness t remains essentially constant. Specifically, this can be quantified to the effect that the wall thickness t at any point of the selected area is not less than 80% and not more than 120% of the mean wall thickness t.

Through the proposed design, it can be achieved that the sole of the shoe has a special spring or cushioning behaviour, whereby, in particular when subjected to the weight of the wearer of the shoe, a predetermined collapse of the sole occurs as a result of the recesses, which provides a pleasant feeling of wear.

REFERENCE NUMERALS

- 2' Recess of the first group
- 2'' Recess of the second group

- 3 Row of recesses
- 4 Row of recesses
- 5 Restriction
- 6 Outer sole
- L Longitudinal direction
- V Vertical direction
- Q Transverse direction
- R1 First direction
- R2 Second direction
- G Biggest dimension of the recess in the first direction
- K Biggest dimension of the recess in the second direction
- k Smallest extension
- t Wall thickness

The invention claimed is:

1. A sole of a shoe, wherein the sole has a longitudinal extension in a longitudinal direction and a vertical extension in a vertical direction that is perpendicular to the longitudinal direction,

wherein a plurality of recesses is provided in the sole that penetrate the sole at least in part, the plurality of recesses extending in a transverse direction that is perpendicular to the longitudinal direction and to the vertical direction,

wherein, without external forces on the sole, a first group of recesses of the plurality of recesses are larger in the vertical direction than in the longitudinal direction and a second group of recesses of the plurality of recesses are smaller in the vertical direction than in the longitudinal direction, the recesses of the first and second groups of recesses having a peripheral contour forming a shape when viewed in the transverse direction,

wherein, at least in sections, at least one row of the first and second groups of recesses is arranged adjacent to another row of the first and second groups of recesses in the longitudinal direction such that a recess of the second group is arranged between two recesses of the first group,

wherein an upper row of recesses and a lower row of recesses are arranged above one another at least in sections in the vertical direction such that a recess of the first group lies vertically above a recess of the second group, and

wherein, without external forces on the sole, a largest first dimension of a recess of the plurality of recesses in a first direction is at least 150% of a largest second dimension of the recess in a second direction that is perpendicular to the first direction such that, when an external force is applied to the sole, the plurality of recesses is configured to collapse.

2. The sole of claim 1, wherein the plurality of recesses penetrate the sole completely in the transverse direction.

3. The sole of claim 1, wherein the plurality of recesses extend along a straight line.

4. The sole of claim 1, wherein without external forces on the sole, the largest first dimension of a recess in the first direction is at least 180% of the largest second dimension of the recess in the second direction.

5. The sole of claim 1, wherein the plurality of recesses has, in a central region, a restriction with a minimum dimension which is at most 90% of the largest second dimension in the second direction.

6. The sole of claim 1, wherein the largest first dimension is between 8 millimeters and 18 millimeters, inclusive.

7. The sole of claim 1, wherein a wall thickness of a material of the sole remaining between the number of recesses is constant at least in sections.

8. The sole of claim 1, wherein the sole comprises a polyurethane material, thermoplastic polyurethane (TPU), or thermoplastic elastomer (TPE).

9. The sole of claim 8, wherein the sole comprises a material that is foamed.

10. The sole of claim 1, wherein the sole comprises a material having a density of between 0.20 g/cm³ and 0.50 g/cm³, inclusive.

11. The sole of claim 1, wherein the sole comprises a material having a hardness of between 30 Asker C and 50 Asker C, inclusive.

12. The sole of claim 1, wherein the sole is or comprises a midsole.

13. The sole of claim 12, wherein the midsole is connected to the upper and an outsole of the sole is arranged below the midsole.

14. The sole of claim 1, wherein the plurality of recesses is arranged in the longitudinal direction over at least 33% of a total distance taken along the longitudinal extension of the sole.

15. The sole of claim 1, wherein the plurality of recesses is arranged at least in a midfoot region and a rearfoot region of the sole.

16. The sole of claim 1, wherein the plurality of recesses of the sole are configured to collapse to produce a spring deflection when the external force is removed from the sole.

17. The sole of claim 1, wherein the shape is of a lemniscate.

18. A shoe, comprising:

an upper; and

a sole structure connected to the upper, the sole structure comprising a midsole connected to the upper and an outsole arranged below the midsole,

wherein the midsole includes a first row of recesses and a second row of recesses that extend through the midsole, the first row of recesses being disposed ver-

5

tically above the second row of recesses such that the first row of recesses is closer to the upper than the outsole and the second row of recesses is closer to the outsole than the upper,

wherein the first row of recesses and the second row of recesses include alternating vertical recesses and horizontal recesses, the vertical and horizontal recesses each having a peripheral contour,

wherein the first row of recesses is arranged adjacent to the second row of recesses such that a horizontal recess of the second row of recesses is arranged below a vertical recess of the first row of recesses,

wherein, without external forces on the sole structure, the vertical recesses are larger in a vertical direction of the sole structure than in the longitudinal direction and the horizontal recesses are smaller in the vertical direction than in the longitudinal direction, the vertical direction being perpendicular to the longitudinal direction, and wherein the first and second rows of recesses are configured to collapse when an external force is applied to the sole structure.

19. The shoe of claim 18, wherein the first row of recesses and the second row of recesses extend across a forefoot region, a midfoot region, and a rearfoot region of the sole structure.

20. The shoe of claim 18, wherein a central region of at least one of the vertical recesses has a restriction with a minimum dimension which is less than or equal to 90% of a largest horizontal dimension taken horizontally of the at least one of the vertical recesses.

21. The shoe of claim 18, wherein all of the vertical recesses and all of the horizontal recesses extend entirely through the midsole.

22. The shoe of claim 18, wherein the peripheral contour forms a shape of a lemniscate.
